UNITED STATES PATENT OFFICE.

JAMES WILLIAM ANDERSON AND WILLIAM JOHN HEMPHILL, OF OTTAWA, ONTARIO,
AND ROBERT RICHARDSON, OF SOUTH MARCH, ONTARIO, CANADA.

OIL BURNER.

Application filed April 7, 1925. Serial No. 21,343.

To all whom it may concern:

Be it known that we, JAMES WILLIAM ANDERSON and WILLIAM JOHN HEMPHILL, both subjects of the King of Great Britain, and residents of the city of Ottawa, in the Province of Ontario, Dominion of Canada, and ROBERT RICHARDSON, a subject of the King of Great Britain, and resident of South March, in the Province of Ontario and Dominion of Canada, have invented certain new and useful Improvements in Oil Burners, of which the following is a specification.

This invention relates to improvements in oil burners adapted to burn crude fuel oil and the objects of the invention are to provide a device of this character by which complete combustion is obtained and which can be controlled by hand with full automatic cut-off.

20 A still further object is to provide a device of this character with semi-automatic control and full automatic cut-off.

Yet another object is the provision of a device of this character of efficient and durable construction, automatically controlled to insure perfect safety in use and obviate all danger from explosion or fire and in which the several parts have been so developed and improved that the machine as a whole will 30 more satisfactorily perform the functions required of it.

With the foregoing and other objects in view, the invention consists essentially in the novel construction and arrangement of parts as described in the present specification and illustrated by the accompanying drawings forming part of the same and in which the essential features are the combination with air and oil feed means of automatic controls 40 whereby, on the power being cut off the flow of oil is automatically cut off and whereby, the device cannot be restarted without being manually operated.

Referring now to the drawings, in which like characters of reference indicate corresponding parts in each figure,

Figure 1 is a side elevation of our improved oil burner,

Figure 2 is a top plan view,

50 Figure 3 is a top plan of the fire pot partly in section.

Figure 4 is a section on line 4—4 of Figure 3,

55 Figure 5 is an enlarged elevation of the motor, fan, pump and latch operating means,

Figure 6 is a perspective view of the latch and bracket members in connection with the switch and oil valve,

Figure 7 is a fragmentary section of the latch and bracket members, 60

Figure 8 is an elevation partly in section through the air and oil feeding means,

Figure 9 is an end view of Figure 8,

Figure 10 is a section through the oil control valve, 65

Figure 11 is a vertical section of the oil shut-off valve,

Figure 12 is a section on the line 12—12 of Figure 5,

Figure 13 is an elevation of a gravity oil feed for oil burners, 70

Figure 14 is a section through the gravity feed float valve, and

Figure 15 is an elevation of a thermostatic control, 75

Referring now more particularly to the drawings, and dealing first with our invention adapted to non-gravity oil feed, A illustrates, in Figure 1 in dotted lines, a furnace and B an oil tank. Within the furnace A on the grate bars is arranged the fire pot 10, hereinafter more fully described, while outside and adjacent the furnace on a suitable stand 11 is mounted a motor 12 provided with a driving shaft 13 on which is mounted the fan 14, communicating through an air supply conduit 15 with the fire pot 10. For forced oil feed a rotary and centrifugal pump 16 is attached to an extension 16^a of the motor shaft 13 (see Figure 5). 80

As illustrated more particularly in Figure 1, fuel oil is delivered to the pump 16 from the service tank B, through an oil line 17, and from the pump delivered, under pressure, through a by-path 19^a to the oil conduit 19 communicating therewith, the surplus fuel oil being returned to the service tank B through the return pipe 18 communicating with the by-path 19^a. In this manner a constant head or pressure of fuel oil is 90 maintained, the oil conduit 19 communicating through oil valve 32 and oil and air regulating valve 21 with the mixing chamber 21^a in the air conduit 15 and thence through the nozzle 22 to the burner 10, the air blast being supplied by the fan 14. 95

From the foregoing it will be seen that on the motor 12 being operated, the pump 16 and fan 14 are operated to supply oil and air respectively to the mixing chamber 110

ber 21^a and from thence to the nozzle 22 into the fire pot 10.

Referring now to the means of supplying power to the motor and the control of such power, as well as the supply of oil and air to the burner, the motor is controlled by means of a double pole electric switch 23 mounted on an extended base plate or bracket 24 and adapted to be connected to the source of power through a plug 25, the current being conveyed from the switch, through a two-conductor flexible cable 26, to the motor 12. For automatically retaining the switch in open position, the switch operating arm or plunger 27 is encased in a sleeve 28 and provided with a spiral spring 29 designed to retain it in open position while to close the switch a lever 30 is provided hingedly connected at 31 to the bracket 24^a and adapted, when swung downwardly, to contact with and move downwardly the spring held switch operating arm 27 closing the circuit. Adjacent the switch 23 and also on the bracket 24 is mounted an oil control valve 32 in the oil conduit 19^a. This oil valve is normally held in closed position by means of a spiral spring 33 wound thereon and is adapted at its upper end to be engaged by the lever arm 30, simultaneously with the switch arm 27, to be pressed downwardly into open position to permit the flow of oil therein. This lever arm is provided with a handle 34 whereby, it is manually operated and when closed down it simultaneously completes the circuit through the switch operating arm 27 and opens the oil valve 32 to permit the flow of oil therethrough. To retain this lever arm in closed position, we provide a pin 35 in a slot 36 in the end thereof designed to engage and disengage with a latch member 37 hingedly mounted at 38 on the bracket 24^a (see Figures 6 and 7).

It will thus be seen that with the lever arm in closed position, as shown in Figure 5, the motor is running, operating the fan and pump through the shafts 13 and 13^a to supply oil and air to the burner. Should, however, through unforeseen circumstances, the supply of electricity be cut off a fly-ball governor 39, having a plunger 40 adapted to be held in position by the centrifugal force of the governor during the normal speed of the fan, is provided on the shaft 13. This plunger 40, in the event of the motor 12 stopping, is forced against the pivotally mounted latch 37 releasing it from engagement with the pin 35, thus allowing the lever arm 30 to move upwardly releasing the pressure on the oil valve 32 and the switch operating arm 27 permitting them to automatically and simultaneously assume their normally closed and open positions respectively, immediately stopping the flow of oil to the burner and breaking the electric circuit.

To start the apparatus again it is necessary to operate the lever arm 30 by hand.

Assuming now that the lever arm has been operated and is in the position shown in Figure 5, and that the motor is running and the oil being delivered through the conduit 19 to the valve 21 and thence to the mixing chamber 21^a and that the air is passing through the conduit 15 also into the mixing chamber 21^a, there to be mixed and passed on through the nozzle 22 into the fire pot 10, control of the oil supply simultaneous with the control of the air supply is provided for and comprises, as illustrated in Figures 1, 8 and 9, a valve 21 inserted in the fuel oil feed pipe 19^a. This valve is connected to a lever arm 43 which in turn is connected through a rod 44 to an arm 45 connected at its other end to the air control valve 46 in the air line 15 and communicating with the mixing chamber 21^a through a passageway 46^a. The nozzle 47 communicating with the oil feed is preferably faced towards the discharge opening 48 of the mixing chamber 21^a communicating with the air line 15.

From the foregoing it will be seen that the rod, which is adapted to be tensioned by means of a turn-buckle 29, is designed on being operated to simultaneously operate the oil line valve 21 and the air line valve 46. To enable this to be done conveniently from a distance we provide an operating rod 50, pivotally connected at its lower end to the rod 44. The arm 45 is vertically retained in position by a coil spring 51 connected thereto and to a plate 52 bolted at 53 on the outside of the mixing chamber whereby, on the rod 50 being pulled upwardly, the rod 44 will be moved to operate the arms 43 and 44 which, in turn, will simultaneously move the valves 46 and 21. When the rod is drawn up to the required position it can be locked there and when released will normally assume the position as shown in Figure 8 and with it the valves 46 and 21, through the influence of the coil spring 51.

From the foregoing it will be seen that on the rod 50, which may be extended to operate the valves from any convenient distance, being moved vertically, the rod 44 will be operated to cause, through the crank arms 43 and 45, the regulating valve 21 and air supply valve 46 to cut off or partially cut off, as may be required, the supply of oil and air to the mixing chamber and thence to the burner. By this simple construction the flame in the fire pot can be regulated and controlled absolutely so that the heat given off thereby is also regulated and controlled accordingly. Furthermore, by means of a thermostat or other suitable means, as illustrated in Figure 15, the valves 21 and 46 and the resulting supply of mixed oil and air to the burner can be automatically con-

trolled, the thermostat being connected in any well known manner to the rod 50 through a pivotally mounted and weighted rod 54, link connected at one end through 5 a link 55 with a lever 56, the thermostat 57 being arranged according to the temperature required to automatically operate the rod 54 to operate the valve control rod 44.

From the mixing chamber 21^a the mixture 10 of air and oil enters, through the line 15 and nozzle thereon 22, the fire pot or burner 10 arranged in the furnace A, preferably on the grate bars or the like. This fire pot, as illustrated more particularly in Figures 3 15 and 4, is formed on the opposite side to that penetrated by the nozzle 22, with a V-shaped baffle or flame dividing plate 22^a. The air and oil mixture as it enters through the nozzle 22 first strikes the floor or base of 20 the pot through the downward bending of the nozzle causing atomization. The flame is then thrown or directed to the back of the fire pot and the flame directed on the inside thereof, the flange 59, shown on the upper 25 side of the fire pot, causing the flame to be deflected from the furnace door and directed towards the centre where final combustion takes place.

Special heat resisting substances may be 30 used within the fire pot to prolong its life and maintain efficient combustion.

In Figures 13 and 14 is illustrated means for supplying oil to the burner by gravity and in which B is the oil supply tank and 35 17 the oil supply line communicating with a float chamber 60 in which there is a combined float and needle valve 61, the oil moving from the chamber 60 through the conduit 17 to the oil supply conduit 19 and, as 40 already described, and thence to the burner via the oil supply valves 32 and 21, and mixing chamber 21^a.

As many changes could be made in the 45 above construction and many apparently widely different embodiments of our invention within the scope of the claims, constructed, without departing from the spirit and scope thereof, it is intended that all matter contained in the accompanying specification and drawings shall be interpreted 50 in an illustrative and not in a limiting sense.

What we claim as our invention is:

1. In an oil burner and in combination, a burner, a fan and an oil supply tank, an 55 air line connecting the fan with the burner, a mixing chamber in the air line, a fuel line connecting the fuel tank with the mixing chamber, prime mover means for operating the fan to supply an air blast to the mixing 60 chamber, valves operable from a distance, for regulating the supply of air and fuel to the mixing chamber simultaneously, a pump operable by the prime mover for delivering fuel under pressure to the mixing chamber, 65 a switch spring-held in open position for

controlling the operation of the prime mover, a control valve in the fuel line spring-held in closed position and a lever arm adapted to simultaneously open said valve and close the prime mover circuit, means for 70 automatically engaging and retaining the lever arm in an operative position and a governor automatically operable, on the prime mover stopping, to release said lever arm. 75

2. In an oil burner of the character described, means for automatically cutting off the supply of oil on the power being cut off, comprising a spring actuated switch for the power supply means and normally held in open position, a spring actuated oil control 80 valve adjacent said switch and normally held in closed position and manually operated means adapted to contact with the operating arm of the switch and the oil valve to simultaneously close the circuit and open the oil valve and means carried by the manually operated means adapted to engage with an operatively mounted latch to hold the former in position and means for automatically releasing the latch on the power being cut off to simultaneously close the oil control valve and open the circuit switch comprising, in combination with a driving motor, 85 a governor provided with a plunger on the motor shaft and designed to be retained in drawn in position on the shaft being rotated and designed on the shaft being stopped to automatically protrude to engage with and release said latch. 90

3. In an oil burner of the character described and in combination, a burner pot adapted to be detachably placed within a furnace or the like, an oil tank, a prime mover, a fan operable by the prime mover, a mixing chamber, an air line connecting the fan and the mixing chamber, an oil line connecting the mixing chamber with the oil tank, a switch, spring held in open position, for controlling the power supply means for the prime mover, an oil control valve in the oil line adjacent said switch and spring held normally in closed position, a pivotally mounted lever arm adapted to contact with the switch and the oil control valve to simultaneously close the switch and open said 100 valve, means for retaining the lever arm in operative lowered position and means carried by the prime mover driving shaft for automatically releasing the lever arm on the shaft ceasing to rotate wherebv, the oil control valve and said switch are automatically and simultaneously returned to normal, closed and opened position respectively, conduit means connecting the mixing chamber with the fire pot. 110

4. In an oil burner of the character described, a prime mover shaft connected to a fan and a pump, an air line connected to the fan and an oil fuel line connected to the pump, a control valve for the oil line 120 125 130

normally held in closed position, a control switch for the prime mover normally held in open position, means for simultaneously closing the switch and opening said control valve and means for retaining the switch in closed position, a governor provided with a plunger on the prime mover shaft whereby, on the latter being rotated, the plunger assumes an inward position and whereby, on the prime mover ceasing to operate, the

plunger automatically protrudes to automatically engage with the switch retaining means to release it and open the switch and, at the same time, close the oil control valve.

In witness whereof we have hereunto set ¹⁵ our hands.

JAMES WILLIAM ANDERSON.
WILLIAM JOHN HEMPHILL.
ROBERT RICHARDSON.
